UNITED STATES PATENT OFFICE.

FRANK E. WILKINSON AND JACOB CHARLES MCNAUGHT, OF KINGFISHER, OKLAHOMA.

DUST-MULSH MACHINE.

1,285,522.

Specification of Letters Patent. Patented Nov. 19, 1918.

Application filed May 23, 1917. Serial No. 170,498.

To all whom it may concern:

Be it known that we, FRANK E. WILKINSON and JACOB CHARLES MCNAUGHT, citizens of the United States, residing at Kingfisher, in the county of Kingfisher, State of Oklahoma, have invented a new and useful Dust-Mulsh Machine, of which the following is a specification.

This invention relates to cultivators of that type known as dust mulsh machines, one of the objects of the invention being to provide a machine of this character which is simple and compact in construction, can be easily moved from place to place, and which utilizes a cultivating blade of novel form designed to cut under the surface of the ground to produce the desired mulsh.

A further object is to provide a blade of this character having means whereby weeds and trash are prevented from accumulating about the end portions of the blade and interfering with the operation of the machine.

A further object is to provide a cultivator of this type which can be adjusted to meet different requirements.

A still further object is to provide means, extending from the blade of the cultivator, for breaking up the soil passing over the blade and for throwing upwardly from the soil any roots, trash, and the like which may be loosened by the blade.

With the foregoing and other objects in view, which will appear as the description proceeds, the invention resides in the combination and arrangement of the parts in the details of construction and hereinafter described and claimed, it being understood that changes in the precise embodiment of the invention herein disclosed can be made within the scope of what is claimed, without departing from the spirit of the invention.

In the accompanying drawings the preferred form of the invention has been shown.

5 In said drawings:—

Figure 1 is a side elevation of the machine.

Fig. 2 is a plan view.

Fig. 3 is a section on line 3—3 Fig. 1.

50 Fig. 4 is a detail view of some of the lifting fingers.

Referring to the figures by characters of reference 1 designates the body of the machine, which, as shown, may be mounted on

if preferred, the machine may be supported by wheels. Arranged transversely on the body of the machine is a shaft 2 adapted to be rotated by a hand lever 3 which is secured thereto, this lever carrying a dog 4 for engagement with a toothed segment 5.

Fixedly secured to the shaft are radial arms 6 and these arms are connected, by links 7, to the up turned ends 8 of a cultivating blade 9. In the structure illustrated the blade 9 is formed in a single strip of metal having a straight front edge which is sharpened, the end portions of the strip being bent at right angles and provided with apertures 10 any one of which is adapted to receive the bolt 11 employed for attaching a link 7 to the blade. The bolt 11, as well as additional bolts 12 may be employed for fixedly attaching to the up turned end 8 guide arms 13 which extend forwardly and are pivotally connected to the body structure 1 as indicated at 14. These arms 13 may be used to support disk colters 15 and in addition to these disk colters, colter blades 16 may be adjustably connected to the up turned ends 8 of the blade 9. If preferred either of the colters can be used independently of the other, and in any direction or at any angle.

The prime object of the colters is to cut or remove trash and weeds which may lie in the paths of the up turned ends 8 and to clear them away from said ends so that the blade 9 and its ends will cut readily through the soil thereby loosening it to produce the desired dust mulsh. Obviously instead of providing the colters close to and directly in front of the ends 8 of the blade, they could be mounted adjacent the front end of the body 1 but in the path of the ends 8 of the blade 9.

For the purpose of breaking up the slice of soil above the blade 9 and elevating to the surface of the soil any weeds, roots, trash or the like, a series of upwardly extending fingers 17 is provided. These fingers are extended from a metal strip 18 which is riveted or otherwise secured to the bottom of the blade 9 near its rear edge. Obviously, therefore, as the blade cuts through the soil, the slice of soil passing thereover will be broken up by the fingers 17 and any trash, roots or the like coming into contact with the fingers will be directed upwardly thereby. These fingers thus act

not only as a harrow for breaking up the soil but also as a means for elevating trash, roots and the like and separating them from the soil. They are particularly useful in digging potatoes and for like purposes.

Not only is the front edge of the blade 9 sharpened but the front edges of the ends 8 are likewise sharpened.

When the machine is drawn over the soil 10 the lever 3 can be shifted readily so as to cause the arms 6 and links 7 to press downwardly on the rear ends of the arms 13. This will cause the blade 9 to press downwardly into the soil where it will be held 15 when the lever 3 is locked. Consequently as the machine moves forward the surface portion of the soil will be sliced and broken up into a dust mulsh, interference with the movement of machine by trash and the 20 like being prevented by the colters and by the sharpened front edges of the ends 8.

By means of the adjustment shown, the blade 9 can be placed at any desired angle relative to the arms 13 and, by means of the 25 lever 3, the blade can be forced any desired distance below the surface of the soil. Thus the machine can be adjusted to meet various requirements.

A machine such as described is capable 30 of a wide range of work, such as cultivating corn, cotton, and tobacco, garden truck, vineyards, orchards, and fields in general. The machines can also be used in harvest-

ing beans, peanuts, onions, cabbages, potatoes, cow peas, etc.

While the blade has been shown connected to a portable structure mounted on runners, it is to be understood that the said blade can be mounted in other manner desired so that it can be used in producing a dust 40 mulsh.

It will also be understood that various changes can be made in the construction and arrangement of parts within the scope of the claim.

What is claimed is:

A machine for producing a dust mulsh upon a hard dry soil, including a flat blade having a front cutting edge, the ends of the blade being upturned and having sharp 50 front edges, a rod connecting said ends, a movable structure, guide arms secured to said ends and pivotally connected to said structure, ground engaging devices connected to the arms, adjusting mechanism on 55 said structure, and link connections between said mechanism and the ends of the blade.

In testimony that we claim the foregoing as our own, we have hereto affixed our signatures in the presence of two witnesses.

FRANK E. WILKINSON.
JACOB CHARLES McNAUGHT.
